FIG. 1

Des. 200,715

PAGE 2

FIG. 2

FIG. 3

FIG. 4

FIG. 1 is a perspective view of a children's lawn swing embodying my new design;

FIG. 2 is an enlarged fragmentary perspective view showing the solid line portions of FIG. 1 in greater detail;

FIG. 3 is a perspective view thereof with the seat backs swung apart; and

FIG. 4 is a top plan view thereof with the seat backs swung together.

The dominant features of my design reside in the portions shown in full lines.

I claim:

The ornamental design for a children's lawn swing, substantially as shown and described.
